UNITED STATES PATENT OFFICE.

EDWARD ARTHUR GEOGHEGAN, OF NEW YORK, N. Y.

STEAM-SUPERHEATER.

1,196,102.

Specification of Letters Patent. Patented Aug. 29, 1916.

Application filed February 27, 1915. Serial No. 11,036.

To all whom it may concern:

Be it known that I, EDWARD A. GEOGHEGAN, a citizen of Great Britain, residing in the borough of Manhattan, city of New York, in the county of New York and State of New York, have invented certain new and useful Improvements in Steam-Superheaters; and I do hereby declare the following to be a full, clear, and exact description 5 of the invention, such as will enable others skilled in the art to which it appertains to make and use the same, reference being had to the accompanying drawings, and to the letters of reference marked thereon, forming part of this specification.

My invention relates to steam superheaters, and consists in the improvements hereinafter pointed out and explained.

The features of my invention are illustrated in the accompanying drawings, in which:—

Figure 1, is a section of a portion of a boiler setting with a portion of a steam boiler and a super-heater in place therein, 25 according to my invention. Fig. 2, is a transverse section of the same, on the line $x-x$ in Fig. 1, looking in the direction of the arrow. Fig. 3, is a view, showing a super-heater placed in a boiler setting, according 30 to my invention, in combination with a horizontal tubular boiler. Fig. 4, is a plan view, partially in section of the tubes and headers shown in Figs. 1, 2 and 3.

In these drawings, A, indicates the tubes 35 of a horizontal water-tube boiler, A', indicates the rear-end header therefor; B indicates the fire wall at the rear end of the furnace grates, (not shown) B', indicates the rear wall of the boiler-setting, B², indicates the combustion chamber, and B³, indicates the side walls thereof.

In the side walls B³, of the boiler setting, I provide recesses C, which communicate with the combustion chamber B, back of the 45 fire-wall B, and in these recesses C, I place in an inclined position, super-heater headers, D, each of which is preferably composed of a plurality of independent chambers d, d² and d⁴, and d' and d³, said headers being 50 connected by means of tubes D', extending from one to the other transversely through said combustion chamber, the said headers D, and tubes D', being higher at the rear end of the combustion chamber B, than at 55 the front end thereof. The recesses C, are closed by means of plates or doors C' so as

to exclude cold air from the combustion chamber B². Steam is introduced into the chamber d through the inlet E, and after traveling through the tubes D', enters the chamber d', of the opposite header D, (see Fig. 4) and thence through the tubes D², into the chamber d², and thence through the tubes D³ into the chamber d³, and lastly through the tubes D⁴, into the chamber d⁴, from whence it passes to the outlet E', of the superheater. The heated gases from the furnace travel rearward of the fire-wall B, over the super-heater tubes, and then upward past the rear end of the baffle-wall a, 70 and while so traveling, heat the super-heater tubes D', D², D³, and D⁴.

It will be obvious to those skilled in the art, that by this arrangement I can obtain the benefit of a moderate drying heat for 75 superheating steam within the tubes D', D², D³, and D⁴, without exposing the tubes to such excessive heat as to injure them, and necessitate a replacing of the same with new tubes.

It will also be obvious that by reason of the intake end of the headers D, being lower than the discharge ends thereof, the super-heater tubes D', do not receive the full force 80 of the heat immediately back of the fire-wall, and that the tubes D', at the rear end of the combustion chamber, being higher, do receive the full force of the heat, so that as the steam travels back and forth through the tubes D across the combustion chamber, 85 it increases in temperature and is subjected to a gradually increasing temperature from without the tubes D'. This arrangement is necessary because as the steam raises in temperature it requires more intense heat 90 to raise its temperature higher.

Having thus shown and described my invention, what I claim as new, and desire to secure by Letters-Patent, is:—

1. In a steam superheating apparatus, a 100 steam boiler, a fire wall, a rear wall, side walls, tube headers located in inclined positions in said side walls, with the ends thereof adjacent to said fire-wall being lower than the ends adjacent to said rear wall, and 105 steam conveying tubes parallel with said fire-wall and connected with said inclined headers, substantially as set forth.

2. In a steam superheater, a steam boiler, a fire-wall, a rear wall, side walls, a plurality of tube-header chambers located in each 110 of said side walls between said fire-wall and

said rear wall, in parallel inclined positions, superheater tubes parallel with said fire-wall connecting the header chambers in one side wall with the header chambers in the 5 opposite side wall, so that steam will be conducted back and forth from the header chambers at one side, to the header chambers at the other side, until it has traversed all of

the chambers and tubes behind said fire-wall, substantially as described.

In testimony whereof I affix my signature, ¹⁰ in presence of two witnesses.

EDWARD ARTHUR GEOGHEGAN.
